UNITED STATES PATENT OFFICE.

GEORGES REYBET, OF JERSEY CITY, NEW JERSEY.

DESIGN FOR A TEXTILE FABRIC FOR DECORATIVE PURPOSES.

56,194.

Specification for Design.

Patented Aug. 24, 1920.

Application filed June 1, 1920. Serial No. 385,839. Term of patent 3½ years.

To all whom it may concern:

Be it known that I, GEORGES REYBET, a citizen of the United States, residing at No. 99 Hague street, Jersey City, in the county of Hudson, State of New Jersey, have invented a new, original, and ornamental Design for a Textile Fabric for Decorative Purposes, of which the following is a specification, reference being had to the accompanying drawing, forming part thereof.

The figure is a plan view of a piece of textile fabric showing my new design.

I claim:

The ornamental design for a textile fabric for decorative purposes, as shown.

GEORGES REYBET.
